UNITED STATES PATENT OFFICE.

JOHN HOVAS, OF NEW YORK, N. Y.

END-GATE FOR DUMPING-WAGONS.

No. 830,073.

Specification of Letters Patent.

Patented Sept. 4, 1906.

Application filed August 9, 1905. Serial No. 273,359.

To all whom it may concern:

Be it known that I, JOHN HOVAS, of New York, in the county of New York and State of New York, have invented certain new and 5 useful Improvements in End-Gates for Dumping-Vehicles; and I do hereby declare the following to be a full, clear, and exact description of the invention, such as will enable others skilled in the art to which it appertains to make and use the same.

The object of this invention is to provide an improved end-gate for vehicles, especially dumping-vehicles, provided with a body designed to be tilted to discharge the load, said 15 gate being so arranged and constructed that it may be readily opened by the attendant when the vehicle-body is in the tilted position and being provided with means whereby the gate when opened will always remain 20 open to its full extent until the entire load has been discharged and it is desired that it shall again be closed when the vehicle-body has been returned to its normal horizontal position, thereby avoiding the defects which 25 a freely-closing end-gate would occasion, owing to its weight being always exerted against the discharging load, tending to choke the discharge-opening and prevent a free delivery.

30 In the accompanying drawings, Figure 1 is a perspective view of a dumping-vehicle embodying the improvements of my invention. Fig. 2 is a similar view illustrating a modification residing in the location of the 35 end-gate with respect to the vehicle-body. Fig. 3 is a perspective view of the end-gate in open position and with its unlatching-lever shown detached. Fig. 4 is a detail or fragmentary view in section.

40 The body 1 of the dumping-vehicle is designed to tilt to discharge its load and is preferably constructed throughout of sheet-metal. It is entirely and permanently closed, except feed-openings controlled by 45 doors 2 and a discharge-opening in its rear, controlled by an end-gate 3. This end-gate is hinged at its upper edge and is provided on its outer face with an eccentrically-pivoted latch-bar 4, designed to rock, so that its ends 50 will engage with hooks 5 at the rear of the sides of the body 1. One of said hooks is downwardly-facing, while the other faces upwardly. In order to rock the latch-bar out of engagement with the hooks 5, I have provided 55 an unlatching-lever 6, which is fulcrumed on a stud 7, projecting from one of the

hooks 5, preferably the upwardly-facing hook. The said lever lies against the side of the hook with its weight so disposed that it normally will be in contact with the lower 6c side of the adjacent protruding end of the latch-bar. The said bar is limited in its swinging movement by stop-pins 8 on the end-gate. In order to maintain the end-gate when opened in a wide-open position, it 65 is provided at one or both of its sides with an upwardly-breaking rule-joint strut 9.

It will be observed that in Fig. 1 the end-gate is located below the meeting flanges 10, that secure together the upper section or top 70 1^a of the vehicle-body and the lower or bottom section 1^b thereof, while in Fig. 2 the end-gate forms a part of said upper section. The object of showing these two different constructions is that Fig. 1 illustrates a 75 dumping-vehicle as it would appear if constructed outright with my invention in view, while Fig. 2 illustrates how my invention may be applied to an already-constructed open-top sheet-metal dumping-vehicle of the 80 kind now commonly employed. In the latter instance the invention practically constitutes part of a cover for the vehicle.

When it is desired to empty the dumping-vehicle, the body is first tilted so that its 85 rear end rests on the ground. Then the attendant by simply pressing his foot against the unlatching-lever can disengage the latch-bar from its fastenings, the end-gate will swing open, and the strut 9 straighten out to 90 maintain it in wide-open position until the entire load has been discharged. The attendant may then return the body 1 to its normal horizontal position and readily close the end-gate. As the attendant's hands 95 may be engaged in holding the body in tilted position until the end-gate is opened, it is manifest that the construction and arrangement herein described whereby he may open the end-gate readily with his foot is advanced 100 100 tageous.

I claim as my invention—

1. In a vehicle of the class described, a body provided at the rear of its stationary side members with oppositely-facing hooks, 105 an end-gate hinged at its upper edge to said body, a latch-bar pivotally mounted on said end-gate with its ends designed to engage said hooks, and an unlatching-lever fulcrumed on the body adjacent one of said ends 110 and designed to contact therewith whereby to rock said latch-bar out of engagement

with said hooks, as and for the purpose set forth.

2. In a vehicle of the class described, a tilting body provided at the rear of its stationary side members with oppositely-facing hooks, one of said hooks having an outwardly-projecting pin or stud, an end-gate hinged at its upper edge to said body intermediate the vertical planes of said hooks, a latch-bar pivotally mounted on said end-gate with its ends designed to engage said

hooks, and an unlatching-lever fulcrumed on said pin or stud and designed to contact with an end of said bar, as and for the purpose set forth.

In testimony whereof I have signed this specification in the presence of two subscribing witnesses.

JOHN HOVAS.
